(57) **CLAIM**

The ornamental design for a flexible printed circuit board for game controllers as shown and described.

DESCRIPTION

FIG. 1 is a rear, right, and bottom perspective view of a flexible printed circuit board for game controllers showing my new design;

FIG. 2 is a front, left and top perspective view thereof;

FIG. 3 is a front view thereof;

FIG. 4 is a rear view thereof;

FIG. 5 is left view thereof;

FIG. 6 is right view thereof;

FIG. 7 is top plan view thereof; and,

FIG. 8 is bottom plan view thereof.
